PRINTING PLATE CLAMP OPERATING MEANS

Oscar Charles Roesen, Brooklyn, N. Y., assignor
to Wood Newspaper Machinery Corporation,
New York, N. Y., a corporation of Virginia

Application December 18, 1930, Serial No. 503,208

9 Claims. (Cl. 101—378)

This invention relates to a means for operating printing plate clamps on the printing cylinder of a press.

The principal objects of the invention are to 5 provide power-operated means for releasing the clamp so that all the plates on a section of the cylinder will be loosened at the same time and ready for removal and so that the operator will have nothing to do but start the power-clamp- 10 operating mechanism to secure the locking of the plates after they are placed in position or their unlocking.

Other objects and advantages of the invention will appear hereinafter.

15 Reference is to be had to the accompanying drawing, in which

Fig. 1 is a side view of a printing plate cylinder and associated parts with the clamping means shown in radial section, illustrating a 20 preferred embodiment of this invention;

Fig. 2 is a sectional view on the line 2—2 of Fig. 1, showing the cylinder and cooperating parts in end elevation, and

Fig. 3 is a view partially in section showing a 25 modification of the power-operating mechanism.

In putting printing plates on a press, the usual custom is to lock them up by clamps which are operated with a screw and necessitate the placing on of a wrench by the operator for pulling 30 the clamps up tight. This invention relates to clamps which are spring pressed into locking position.

The plate cylinder 10 is provided with an end clamp 11 mounted in longitudinal slots 12 at the 35 end of the plate cylinder. Each clamp 11 is provided with two or more rods 13 extending inwardly longitudinally of the cylinder and fixed to the clamp between a shoulder on the rod and a nut on the extreme outer end of the rod. This 40 rod is provided with a collar 14 fixed to it and between this collar and a shoulder in a recess 15 in the cylinder, through which the rod passes, is mounted a spring 16. This spring therefore returns the plate clamp to its locked 45 position, where a bevel surface 17 on the plate clamp engages the edge of the plate P, and holds it there.

Preferably two such rods and springs are employed for each clamp. It is well understood 50 that each clamp extends substantially around half of the end of the cylinder so that the cylinder can be turned to two positions diametrically opposite each other for removing and replacing the plates. However, any desired number of 55 these rods can be used on each plate. Of course,

there are clamps at the other end of the cylinder for the same purpose.

The end plates are held in position between surfaces 17 and similar surfaces on the slideable center clip 18. This center clip also holds the ends of the center plates P'. Each rod 13 passes through the center clip 18 and is provided with a head 20 beyond it. Consequently, when the rods are drawn out, the center clip comes with them and releases that edge of the inside printing plates P'. It will be seen that the center clip 18 moves only after the end clip 11 has released the outer end of the plate P so that both plates are fully released.

The end clamp 11 carries two projections 21 which extend beyond the end of the plate cylinder and are perforated for the mounting of a shaft 22. By this shaft a lever 23 is pivotally connected with the clamp. It is also pivotally mounted on brackets 24 mounted on the end of the plate cylinder. The opposite end of the lever 23 is bifurcated and carries a shaft 26 on which is a cam roll 25.

It will be seen therefore that when the parts are in the position shown in Fig. 1 the springs 16 pull the end clip in and clamp both plates P and P'. It also draws in the shaft 26 and cam roller 25.

On the outside of the press frame F is mounted a motor 27 carrying a pinion 28 on its shaft. This pinion, through a gear 29 and a worm 30, integral therewith preferably, rotates a worm wheel 31. This worm wheel has an internal thread cooperating with screw-threads on a reciprocable push rod 32 carried by the frame. This push rod is slidingly keyed so that it cannot turn. Therefore the operation of the motor will move this rod longitudinally in one direction or the other. A bracket 33 is fixed on the frame and acts as a guide for the push rod 32 and also to prevent side movement of the worm wheel 31. The push rod 32 has a head 34 on the inner end.

When it is desired to unlock the plates on the press, the press is stopped at a plating position and the motor is connected with the line so that it will rotate the train of gears to move the push rod 32 to the left. The head 34 engages the cam roll 25, pushing it to the left and consequently pulling the end clamp 11 to the right, resisted by the springs 16. When the operator has finished his plating he connects the motor in the reverse direction, which withdraws the push rod and again allows the springs to relock the plates.

It will be observed that at the end of each 110

cylinder carrying semi-cylindrical printing plates as usual there are two plating positions diametrically opposite. This one operating mechanism serves for both.

5 In Fig. 3 is shown a modification of the operating mechanism to be used in connection with the locking mechanism, the same as shown in Fig. 1. In this case the force required for unlocking the plates is supplied by a cylinder 40 and piston 41. Air or other fluid under pressure 10 is admitted through a valve 42 to force the piston to the left. The rod 43 of this piston is the equivalent of the rod 32 in the other case. The valve 42 is a well known type of valve 15 arranged so that rotation in one direction admits live pressure to one side of the piston and rotation of the valve in the opposite direction not only cuts off the live pressure but opens the exhaust. The push rod 43 is returned in the 20 latter case by a spring 44 operating against a collar 45 on the push rod. This action, of course, allows the clamp springs 16 to operate to relock the plates on the cylinder.

In either case it will be seen that the operating 25 mechanism is independent of the cylinder and so located that, when the cylinder is moved to either of its two opposite positions for plating, the cam roll 25 will be in position to be operated by the head of the push rod. The plates are all 30 released automatically and the clamps kept unlocked until the new plates are put on and then the operating means is withdrawn so that the springs will relock the plates.

Although I have illustrated and described only 35 two forms of the invention I am aware of the fact that modifications may be made therein by any person skilled in the art without departing from the scope of the invention as expressed in the claims. Therefore I do not wish to be limited in this respect but what I do claim is:—

40 1. In a device for operating a plate clamp on a cylinder of a printing press, the combination of a rod mounted on the frame of the press, power-operated means for moving the rod longitudinally toward and from the cylinder and 45 means supported by the cylinder and separate from the clamp adapted to be engaged by said rod for withdrawing the plate clamp.

50 2. The combination with a printing press plate clamp and yielding means for holding it in clamped position against the plates, of power-operated means for forcing the clamp back to unlock the plate comprising a rod movable toward the cylinder and a lever pivoted to the cylinder and having one end in position to be 55 engaged by said rod and the other end connected with the plate clamp.

60 3. In a device for operating a plate clamp on a cylinder of a printing press, the combination of a rod mounted on the frame of the press, power-operated means for moving the rod longitudinally toward and from the cylinder, means 65 supported by the cylinder and independent of the plate clamp adapted to be engaged and operated by said rod for withdrawing the plate

clamp, and yielding means carried by the cylinder for returning the clamp to clamping position when the rod is moved away from the cylinder.

4. In a device for operating a plate clamp, 80 the combination of a motor, a worm wheel operated by said motor and threaded internally and centrally, a rod having a screw-thread meshing with the threads in the worm wheel mounted on the frame to reciprocate, said rod having a head, a lever carried by the plate cylinder and having a cam roll at one end in position, when the cylinder is in plating position, to be actuated by the head of the rod, the other end of the lever being pivotally connected with 85 the plate clamp to withdraw it from clamping position.

5. In a device for operating a plate clamp, 90 the combination of a rod mounted on the frame of the machine and having a head for operating the plate clamp, a piston on the other end of the rod, a cylinder in which the piston is located, means for introducing fluid under pressure for moving the rod into position for operating the plate clamp and a spring for moving 100 the piston back when the fluid behind it is exhausted.

6. In a plate clamp for a printing cylinder, the combination with the cylinder having a longitudinal recess, an end clamp, and a slidable center clip, of a rod in said recess, a compression spring on the rod to hold the rod yieldingly in plate locking position, the rod having means for unclamping the center clip after the end clamp moves to unclamp the end plate on the 110 cylinder.

7. In a plate clamp for a printing cylinder, the combination with the cylinder having a longitudinal recess, an end clamp, and a slidable center clip, of a rod in said recess, a spring 115 on the rod, one end of the spring engaging a fixed part of the cylinder, a collar on the rod which is engaged by the other end of the spring to hold the rod yieldingly in plate locking position, the end clamp being fixed to the rod, the 120 rod being slidably connected to the center clip and having means for unclamping the center clip after the end clamp moves to unclamp the end plate on the cylinder.

8. In a printing plate lock up, the combination 125 of an end plate clamp, a movable center clip, a rod slidably connected with the center clip and fixed to the end clamp, and a compression spring on the rod for forcing the end clamp into locking position, for the purpose described.

9. The combination with a plate clamp for a printing plate cylinder and yielding means for holding it in, and returning it to, clamped position, of means mounted on the cylinder and movable independent of the plate clamp for 135 withdrawing the clamp, and independently mounted means for operating the means on the cylinder to withdraw the clamp in opposition to said yielding means.

OSCAR CHARLES ROESEN. 140
